UNITED STATES PATENT OFFICE.

WILLIAM BARTHOLOMAE, OF NEW YORK, N. Y., ASSIGNOR OF ONE-HALF TO HARRY ZIMMERMAN, OF NEW YORK, N. Y.

SOUNDING TOY.

976,718.

Specification of Letters Patent. Patented Nov. 22, 1910.

Application filed June 3, 1910. Serial No. 564,786.

To all whom it may concern:

Be it known that I, WILLIAM BARTHOLOMAE, a citizen of the United States, residing at the borough of Manhattan, in the city, county, and State of New York, have invented certain new and useful Improvements in Sounding Toys, of which the following is a specification, reference being had to the accompanying drawings.

10 This invention relates to improvements in toys and particularly to improvements in sounding toys in the nature of rattles; and an object of this invention is to provide a sounding toy which will be simple 15 in construction, relatively cheap in manufacture and most efficient in use.

Another object of this invention is to provide a sounding toy the resultant tone given forth by which will be a composite of 20 a plurality of tones.

In the drawings illustrating the principle 25 of this invention and the best mode now known to me of applying that principle, Figure 1 is a plan of my new sounding toy; Fig. 2 is a section on the line A—A of Fig. 1; Fig. 3 is a plan of a modified form of 30 my new sounding toy; Fig. 4 is a section on the line B—B of Fig. 3; and Fig. 5 is a detail showing the connection of a spring-arm to a ball.

Referring particularly to Figs. 1 and 2, the sounding toy therein illustrated is provided with a suitable carrier-body *a* which is formed at one end with a handle *b* and 35 in the other end of which is mounted a rod or post *c*. Upon the free end of the latter is mounted a ball or knob *d*. The handle *b* is formed with a channel *e* through which passes a spring-metal band *f*. The 40 latter is fastened by the staples *g* to the carrier-body *a*. The ends of the spring metal band or leaf-spring *f* are bent to form hooks *h* which are mounted in the holes *i* formed in the bases of the sounding members *j*, *j'*. The latter are formed with sockets *k*; and the walls of each socket *k* are slotted, as is shown at *m*. When the toy is shaken, the sounding members *j*, *j'* strike 45 against the knob or ball *d* in rapid succession. Since the sounding members *j*, *j'* may be of different tones, the resultant tone given forth by the toy will be a composite of the individual tones of the sounding members.

55 Referring to the modified form shown in

Figs. 3 and 4, the carrier body *a'* is formed at one end with a handle *b'* and at its other end with a stationary sounding member *j''* having a socket *k'* the wall of which is formed with slots *m'*. The carrier body is 60 formed with apertures or recesses *z'* in which engage the hooks *h* formed on the lower ends of the spring arms *f'*. The upper ends of the latter are also hook shaped or formed with hooks *h*, which engage in 65 the holes or apertures *i* in the bases of the sounding members *j*, *j'*. In this form the tones of the sounding members *j*, *j'*, *j''* may all vary or be different; and these tones may be so selected that the resultant tone 70 produced by shaking the toy will be a chord.

In Fig. 5 there is shown a non-sounding striking member *n* formed with a recess *z''* in which engages the hook shaped end *h* 75 of a spring arm *f'*. This figure is intended to show that the same mode of connection between a non-sounding striking member and the carrier body may be used as in the case of a sounding striking member. 80

The mode of fastening the spring-arms to the striking members and to the carrier-body is much superior to any mode now known to me of accomplishing the same purpose, because the fastening itself is much 85 more efficient and secure and it is moreover very easy to make, whereby economy of production is attained.

The volume of sound given out by the 90 toys shown in Figs. 1 to 4 inclusive, is much greater than the volume of sound given out by the toys of this character heretofore made. The user may interpose momentarily a finger between the spring-arm support of one of the sounding members and 95 the carrier-body; and by using the sounding members *j*, *j'* alternately and then in unison many new, interesting and amusing results may be produced. These sounding members *j*, *j'*, are freely suspended and 100 their capacity for sustained vibration is greatly increased by such suspension. Further, the pendulum-like movement of the vibrating sounding members effects the volume and quality of the tone. 105

I claim:

1. A sounding toy having in combination a carrier; spring-arms supported thereby; and sounding members which have different tones and which are fitted on the free ends 110

- of said spring-arms arranged to strike against the carrier, when the toy is shaken.
2. In combination in a sounding toy, a carrier which is formed with an aperture; a striking member formed with an aperture; and an arm which connects said carrier and striking member and which is formed with hooks which engage the walls of said aperture.
- 10 3. In combination in a sounding toy, a carrier formed with an aperture; a striking member; and an arm which connects the latter to said carrier and is bent back upon itself at one end, which engages in said aperture.
- 15 4. In combination in a sounding toy, a carrier; a striking member formed with an aperture; and an arm which connects said striking member and carrier together and which is bent back upon itself at one end, the latter engaging in said aperture.
- 20 5. In combination in a sounding toy, a carrier; a striking member formed with an aperture; and a spring arm which connects said striking member and carrier together and which is bent back upon itself at one end, the latter engaging in said aperture.
- 25 6. In combination in a sounding toy, a carrier formed with an aperture; a striking member; and a spring arm which connects said striking member and carrier together and which is bent back upon itself at one end, the latter engaging in said aperture.
- 30 7. A sounding toy having in combination a carrier provided with a stationary sounding member; and a spring-mounted sounding member carried by said carrier and adapted to strike against said stationary sounding member, when the toy is shaken.
- 35 40 8. A sounding toy having in combination a carrier provided with a sounding member; and a pair of spring-mounted sounding members carried by said carrier and ar-
- ranged on opposite sides of said sounding member and to strike thereagainst, when the toy is shaken.
9. A sounding toy having in combination a carrier-body provided with a sounding member; and a pair of sounding members which have different tones and which are spring-mounted and carried by said carrier-body; said spring-mounted sounding members being arranged to strike against the first-named sounding member, when the toy is shaken.
10. A sounding toy having in combination a carrier provided with a sounding member; a spring-arm supported by said carrier; and a sounding member fitted on said spring-arm and arranged to strike against the first-named sounding member, when the toy is shaken; said sounding members having different tones.
11. A sounding toy having in combination a carrier provided with a sounding member; and a pair of sounding members which are spring-mounted and carried by said carrier; said spring-mounted sounding members being arranged to strike against the first-named sounding member and two of said sounding members having different tones.
12. A sounding toy having in combination a carrier; a spring-arm supported thereby; and a hollow sounding member detachably fitted on the free end of said spring-arm and arranged to strike against said carrier, when the toy is shaken.
- In testimony whereof I hereunto set my hand at New York City, N. Y., this twenty-seventh day of May, 1910, in the presence of the two undersigned witnesses.
- WILLIAM BARTHOLOMAE.
